UNITED STATES PATENT OFFICE

GEORGE A. BUTTRESS, OF LOS ANGELES, CALIFORNIA

MECHANISM FOR FORMING LATH PANELS

Application filed February 4, 1929. Serial No. 337,492.

This invention relates to a mechanism for forming fabricated lath panels and particularly pertains to a machine for forming sheet rib lath of the character set forth in Letters Patent of the United States, Number 1,753,598, issued April 8, 1930, and which lath embodies spaced parallel ribs formed of a plastic composition interposed between fibrous facing and backing sheets; the invention also pertaining to a mechanism for forming the ribs of the lath with a dove-tail cross section employed in the method for forming such lath as disclosed in Letters Patent of the United States, Number 1,791,791, issued February 10, 1931.

An object of the invention is to provide a mechanism whereby a ribbon or strip composed of a longitudinally corrugated sheet having composition ribs formed on one side thereof and covered by a backing sheet may be worked while the ribbon is advancing to form the composition ribs and the spaces therebetween, of dove-tail cross section and at the same time compress the composition to render it compact.

Another object is to provide a combined press and rib forming mechanism operable to advance with the work while effecting the pressing and forming operation, and also operable to be retracted out of operative relation to the work, whereby the forming and pressing operations will be effected intermittently on a continuously advancing ribbon.

Another object is to provide a mechanism so timed that the rib forming and pressing operations will be performed substantially coincidently.

Another object is to provide an effective means for forming substantially rectangular composition filled corrugations with overhanging side walls operable by pressing the side walls laterally from vacant corrugations.

Another object is to provide a rib lath forming mechanism in which a ribbon of the lath will be formed preparatory to division into dimensioned panels and in which the ribs are so formed as to permit longitudinal severance of the ribbon into a plurality of widths including means whereby the facing and backing sheets may be joined to-

gether contiguous the line of severance in such manner as to be held against separation from each other during the severing action.

A further object is to provide a mechanism of the above character which will enable rapid out-put of the product.

With the foregoing objects in view, together with such other objects and advantages as may subsequently appear, the invention resides in the parts and features and in the combination, construction and arrangement of parts hereinafter described and claimed and illustrated by way of example in the accompanying drawings, in which:

Fig. 1 is a view of the machine as seen in side elevation;

Fig. 2 is an end view with portions broken away as seen in the direction indicated by the arrow 2 in Fig. 1;

Fig. 3 is a view in elevation with portions broken away as seen in the direction indicated by the arrow 3 in Fig. 2;

Fig. 4 is a fragmentary plan view as seen on the line 4—4 of Fig. 3;

Fig. 5 is a view as seen on the line 5—5 of Fig. 4 in the direction indicated by the arrows, illustrating one of the rib forming devices as seen in side elevation with portions removed;

Fig. 6 is a detail in section and elevation as seen on the line 6—6 of Fig. 5;

Fig. 7 is an enlarged detail in section illustrating the manner of forming and compacting the lath ribs.

Referring to the drawings more specifically, A and B indicate spaced horizontal frame members which are mounted on suitable supports and on which are carried parallel horizontally extending tracks C and D on which is supported, for reciprocal movement, a carriage E embodying side rails F and G, each of which is fitted with sets of rollers H and I for traversing the tracks C and D. Reciprocal movement of the carriage E is here shown as effected by rotation of a shaft J fitted with a wheel K carrying a wrist pin L engaging one end of a connecting rod M leading to and attached to a hanger N depending from the under side of a bed plate 100.

O embodied in the carriage E; the bed plate being carried on the rails F and G.

Supported on the bed plate O, is a table P over which is fed a lath ribbon Q (shown in Fig. 1) which ribbon, as shown in Fig. 7, embodies a longitudinally corrugated facing sheet a, a backing sheet b, and composition ribs c which ribs are formed in alternate corrugations of the sheet a and consists of a wet unstable plastic composition as initially formed previous to feeding the ribbon over the table P, and which composition hardens when dry to form with the sheets a and b, the finished product. The corrugations of the sheet a and the ribs c as initially formed are of substantially rectangular cross section affording vacant corrugations between adjacent ribs c also of substantially rectangular cross section. In initially forming the ribbon Q, the facing sheet a is formed with its longitudinal corrugations in any suitable manner, not necessary to be here shown, and is fed to the machine embodying the present invention in a horizontal position over a platform R in any suitable manner; the plastic composition being placed in the alternate upwardly opening corrugations of the sheet a, and the backing sheet b being imposed thereon as the ribbon advances over the platform R previous to feeding of the ribbon over the table P.

Fitted on the table P, and extending longitudinally thereof adjacent its side edges are upwardly extending fixed flanges 8 and 9, the adjacent or inner faces of which are bevelled inwardly, as indicated at 10 in Fig. 7, and over which flanges the marginal portions of the sheets a and b of the ribbon Q extend as the latter advances over the table, with the marginal ribs c of the ribbon extending contiguous the bevelled faces of the flanges 8 and 9. The table P is also provided with one or more fixed flanges 11, shown in Fig. 2, the side faces of which are bevelled inwardly, being here shown as provided with one of such flanges extending intermediate the flanges 8 and 9. Mounted on the table P is a series of spaced rib-pressing and forming members S which project above the top face of the table and which extend in parallel relation to each other and to the flanges 8, 9 and 11 and which are arranged to extend into the vacant corrugations between adjacent ribs of the ribbon Q. Each of these forming devices S embodies a pair of spaced vertically extending relatively movable side plates 12 and 13 arranged in longitudinal slots 14 formed in the table P, and normally seating against the sides of the slots as shown in Fig. 7, and interposed between each pair of plates 12 and 13 is a vertical reciprocal spreader 15 having an upper marginal portion formed with a flat top face d and provided with inclined side faces e and f converging downwardly toward each other. The faces e and f seat on longitudinal ribs g and h formed on

the inner faces of the plates 12 and 13 and extending longitudinally thereof on a plane above the upper face of the table P; the inclined faces e and f and ribs g and h being so arranged that on downward movement of the spreader 15, the plates 12 and 13 will be rocked on the upper margins of the side walls of the slot 14 so that the plates 12 and 13 will be disposed in oppositely inclined positions and indicated in dotted lines in Fig. 7, and whereby the upper end portions of the plates will press the side walls of the corrugations of the ribbon Q into dove-tail cross section. The spreader 15 is in the form of a bar extending substantially throughout the length of the plates 12 and 13 and is interconnected therewith by means of pins 16 and 17 projecting from the opposite sides of the spreader bar and extending into vertical slots 18 and 19 in the plates 12 and 13 as particularly shown in Figs. 5 and 6. Formed on the spreader bar at intervals throughout its length is a series of depending stems 20 and extending transversely beneath the spreaders is a series of rock shafts 21, each of which is formed with a series of cams 22 which seat in openings 23 formed in the aligned stems 20 of the contiguous spreader bars; the outer ends of the rock shafts 21 projecting from one side of the table P and being fitted with cranks 24 pivotally connecting with an actuating bar 25, whereby longitudinal movement of the bar 25 will rock the series of rock shafts 21 collectively and thereby effect simultaneous movement of the spreader bars. As a means of operating the bar 25, the outer end of the latter is pivotally connected to a lever 26 pivoted at 27 on the carriage rail E; the lower end of the lever being adapted to be engaged by a fixed projection 29 on the frame member A as shown in Fig. 3. The lower end of the lever 26 is fitted with a pivotally supported spring pressed finger 30 adapted to ride over the projection 29 when the carriage E is moved rearwardly from the position shown in Fig. 3 without effecting operation of the lever 26 and being operable to engage the projection 29, as indicated in dotted lines in Fig. 3, to actuate the lever 26 on forward movement of the carriage E. As a means for restoring the lever 26 and its connections to a normal position after actuation of the lever by the projection 29, a link 31 is connected to the upper end of the lever 26 and extends horizontally and rearwardly therefrom; the link being formed with an elongated slot 32 through which projects a pin 33 fixed relatively to the frame A and here shown as mounted on a standard 34; the pin 33 being arranged to engage the outer end of the slot 32 when the carriage E advances to a point after which the lower end of the lever 26 has been engaged by the projection 29 and passed thereover so that the continued movement of the carriage will re-

store the lever 26 to normal. The spreader bars 15 are normally disposed in their uppermost position, as shown in Fig. 7, in which position, the actuating bars 25 and 26 will be disposed as shown in full lines in Fig. 3. These parts are thus disposed throughout retrograde movement of the carriage E and being operated to effect spreading of the plates 12 and 13 during the forward movement of the carriage E at a point at or near the middle of the length of its stroke and at such point in its movement that continued forward travel of the carriage will cause the pin 33 to act through the link 31 to restore the spreader parts to normal. As before stated, the spreader bar 15 in moving downwardly spreads the upper end portions of the plates 12 and 13. On upward movement of the spreader bar 15, the plates 12 and 13 are caused to assume their normal parallel position by their lower end portions gravitating to vertical which is assisted by the upper portions of the plates being engaged by the advancing side walls of the corrugated ribbon.

Means are provided for pressing the ribbon as it advances and while the spreader is operating in forming the dove-tail channels. This means embodies a press T extending over the table P and mounted for vertical movement on guides 35 erected on the plate O. A pair of connecting rods 36 and 37 engage with trunnions 38 on each end of the press T and the lower ends of the connecting rods connect with eccentrics 39 formed on the ends of a pair of parallel shafts 40 and 41 journaled on hangers 42 and 43 depending from the carriage E. The shafts 40 and 41 are designed to be rotated in unison to effect reciprocation of the press T for which purpose a pair of intermeshing gear wheels 44 and 45 are mounted on the shafts 40 and 41 respectively. Rotatively supported on the shaft 41 is a fly wheel 46 around which passes a belt 47 taut irrespective of movement of the carriage E throughout the stroke thereof. Keyed on the shaft 41 is a clutch 48 encompassed in a housing 49 carried on the hanger 43, and which clutch carries, a spring pressed retractable tooth 50 adapted to be advanced into engagement with a notch 51 on the fly wheel 46 whereby rotation of the fly wheel will effect rotation of the clutch 48 and shafts 40 and 41. The tooth 50 is normally held in a retracted position out of engagement with the notch 51 by means of a trip lever 52 one end of which is adapted to be positioned in front of the tooth 50 as shown in Fig. 2. The trip lever is pivoted on a trunnion 53 carried by the housing 49 and has its outer end connected through a link 54 with a lever 55 pivoted at 56 on a bracket 57 carried by the hanger 43. A spring 58 normally holds the trip lever in its tooth engaging position in which position a lug 59 on the trip lever seats on the clutch 48 to serve as a support for

limiting rocking movement of the trip lever under the urge of the spring 58. The lever 55 is normally held in an advanced position by means of a spring 61. The lower end of the lever 55 is adapted, on forward movement of the carriage, to engage a fixed abutment 62 in such manner as to actuate the trip lever to move the latter from in front of the tooth 50 and thereby permit the tooth to move into engagement with the notch 51 on the fly wheel. This actuation of the lever 55 and the trip lever 52 occurs during one revolution of the fly wheel 46; the lever 55 and trip lever 52 being restored to normal under the urge of the springs 58 and 61 on the lower end of the lever 55 passing over the abutment 62. The trip lever will then be positioned to re-engage the tooth 50 as the clutch revolves to throw the clutch out of operative engagement with the fly wheel on completion of one revolution of the clutch. A suitable brake 63 is employed for stopping rotation of the clutch 48 on disengagement of the fly wheel from the latter. This rotation of the clutch effects one revolution of the shafts 40 and 41 and the cams 38 and 39, thereby effecting a reciprocal movement of the press T, the timing of which is so arranged that the downward movement of the press will occur substantially coincidentally with downward movement of the presser or spreader bars 15, that is to say while the carriage E is advancing and at a point at or near the middle of its forward stroke. On rearward movement of the carriage, the lower end of the lever 55 rides over the abutment 62, the lever then rocking in opposition to the spring 61 which movement is permitted by a pin and slot connection between the link 60 and the trip lever.

As a means for effecting interconnection between the marginal portions of the sheets *a* and *b* of the ribbon Q as the latter advances between the table P and the press T, these marginal portions pass between a pair of rollers V and W shown in Fig. 1; the roller V being formed with a series of radially extending pins X and the roller W being formed with a peripheral channel so that as the contacting sheets A and B pass therebetween, the pins X will press portions of the sheet B into and downwardly through the sheet A as indicated at Y in Fig. 7. A similar pair of rollers are provided to press two rows of interengaging tangs in the portion of the sheets passing astride the central rib 11, as indicated in dotted lines Z in Fig. 2 so as to effect interconnection of the sheets *a* and *b* along a line intermediate their margins; the ribbon being designed to be secured longitudinally between the rows of the interconnections thus formed.

In carrying out the invention, the flanges 8, 9 and 11 and forming ribs S are formed to project above the top surface of the table P a distance less than the depth of the corruga-

tions of the ribbon Q, as shown in Fig. 7, whereby a clearance is afforded between these members and the bottoms of the corrugations engaged thereby when the ribbon is seated on the table P. This clearance affords a slack in the corrugated sheet which slack is taken up on spreading the upper ends of the plates 12 and 13 and when the press F is caused to press against the ribbon as indicated in dotted lines in Fig. 7.

10 dotted lines in Fig. . . .
The advance movement of the carriage E is timed to correspond with the advance movement of the ribbon Q so that the vertical and lateral pressing actions on the corrugations of the ribbon may be effected while the latter is being continuously advanced.

Any suitable means may be employed for effecting advance of the corrugated ribbon and for effecting its continuous movement while being operated on by the press. Thee rollers V and W may be employed as a means for feeding the ribbon or at least assist in so doing, in which event the roller V may be driven in any suitable manner.

25 While I have shown and described a specific embodiment of the invention, I do not limit myself to the exact details of construction and arrangement shown, but may employ such changes and modifications as occasion 30 may require without departing from the spirit of the invention as defined in the accompanying claims.

I claim;

1. In a machine for forming fabricated lath panels, means for advancing a ribbon having a series of parallel longitudinally extending plastic composition ribs of substantially rectangular cross-section covered with fibrous facing sheets, and means operable to press the side walls of the ribs inwardly while the ribbon is advancing.

2. In a machine for forming fabricated lath panels, means for advancing a ribbon having a series of parallel longitudinally extending plastic composition ribs of substantially rectangular cross-section covered with fibrous facing sheets, means operable to press the side walls of the ribs inwardly while the ribbon is advancing, and means operating co-incidentally with said last named means to compress said ribs.

3. In a machine for forming fabricated lath panels, means for continuously advancing a ribbon composed of a facing sheet having substantially rectangular corrugations extending longitudinally thereof, with the corrugations on one side of the sheet thereof filled with a plastic composition and covered by a backing sheet, means for pressing the ribbon while it advances to compress the plastic composition, and means cooperating coincidently with said last named means to convert the corrugations into substantially dove tail cross-section.

4. In a machine for forming fabricated

5. In a machine for forming fabricated 80
lath panels, means for continuously advancing
a ribbon composed of a facing sheet having
substantially rectangular corrugations
extending longitudinally thereof, with the 85
corrugations on one side of the sheet thereof
filled with a plastic composition and covered
by a backing sheet, means for pressing the
ribbon while it advances to compress the plastic
composition, means cooperating with said 90
last named means to convert the corrugations
into substantially dove-tail cross-section,
means for effecting inter-engagement between
the facing and backing sheet along the margins
thereof, and means for effecting inter- 95
engagement between the facing and backing
sheet intermediate the margins thereof.

6. In a machine for forming fabricated lath panels, means for advancing a ribbon having a series of parallel longitudinally extending composition ribs of substantially rectangular cross-section covered with fibrous facing sheets, a press operable to compress the composition ribs while the ribbon is advancing, and means extending between adjacent ribs of the advancing ribbon, movable toward and away from the sides of said ribs for compressing said ribs laterally while the ribbon is advancing.

7. In a machine for forming fabricated lath panels, means for advancing a ribbon having a series of parallel longitudinally extending composition ribs of substantially rectangular cross-section covered with a flexible facing sheet, a reciprocal carriage, a table on said carriage over which the ribbon is passed, a press on said carriage, means for actuating said press as the carriage advances to compress the ribs, a series of pairs of parallel plates projecting upwardly from said table arranged to project between the composition ribs of the ribbon, and means for spreading the upper margins of the plates of each pair against the sides of the ribs while the carriage and ribbon are advancing. 110 115 120

8. In a machine for forming fabricated lath panels, means for advancing a ribbon having a series of parallel longitudinally extending composition ribs of substantially rectangular cross-section covered with a flexible facing sheet, a reciprocal carriage, a

- table on said carriage over which the ribbon is passed, a press on said carriage, means for actuating said press as the carriage advances to compress the ribs, a series of pairs of parallel plates projecting upwardly from said table arranged to project between the composition ribs of the ribbon, spreader bars extending between the pairs of plates, means operable on advance of the carriage to depress and elevate said spreader bars, and means whereby downward movement of said bars will press said plates against the sides of the composition ribs.
9. In a machine for forming fabricated lath panels, means for advancing a ribbon having a series of parallel longitudinally extending composition ribs of substantially rectangular cross-section covered with a flexible facing sheet, a reciprocal carriage, a table on said carriage over which the ribbon is passed, a press on said carriage, means for actuating said press as the carriage advances to compress the ribs, a series of pairs of parallel plates projecting upwardly from said table arranged to project between the composition ribs of the ribbon, spreader bars extending between the pairs of plates, means operable on advance of the carriage to depress and elevate said spreader bars, means whereby downward movement of said bars will press said plates against the sides of the composition ribs, and means whereby movement of said press and spreader bars will be controlled by movement of said carriage.
10. In a machine of the character described, a horizontally movable carriage, means for reciprocating said carriage, a vertically movable press on said carriage, means for reciprocating said press while the carriage is in motion, and a series of oppositely movable pressing members on said carriage beneath said press.
11. In a machine of the character described, a horizontally movable carriage, means for reciprocating said carriage, a vertically movable press on said carriage, means for reciprocating said press while the carriage is in motion, a series of oppositely movable pressing members on said carriage beneath said press, and means controlled by movement of said carriage for actuating said members.
12. In a machine of the character described, a horizontally movable carriage, means for reciprocating said carriage, a vertically movable press on said carriage, means for reciprocating said press while the carriage is in motion, controlled by movement of the carriage, and a series of oppositely movable pressing members on said carriage beneath said press.
13. In a machine of the character described, a horizontally reciprocal carriage, a series of pairs of parallel laterally rockable plates carried on said carriage, a spreader
- arranged between the plates of each pair, and means for actuating said spreaders controlled by movement of said carriage.
14. In a machine of the character described, a rib forming member comprising a pair of parallel horizontally extending plates supported for tiltable movement, shoulders on the contiguous faces of said plates, a vertically reciprocal spreader bar between said plates having inclined faces seating on said shoulders, and means for actuating said bar to effect spreading of said plates.
15. In a machine of the character described, a horizontally reciprocal carriage, a vertically movable press guided on said carriage, pitmen supporting said press, normally stationary shafts connected to said pitmen, and means controlled by movement of said carriage for intermittently rotating said shafts.
16. In a machine for forming panels consisting of a plastic composition interposed between a facing and a backing sheet, means for punching the marginal portions of the sheets to form tangs, and means for pressing the tangs into inter-engagement.
17. In a machine for forming fabricated lath panels, a horizontally movable carriage, means for reciprocating said carriage, a vertically movable press on said carriage, means for reciprocating said press while said carriage is in motion, and means cooperating between said press and carriage for compressing a ribbon interposed therebetween.
18. In a machine for forming fabricated lath panels, a horizontally reciprocal carriage, a vertically movable press on said carriage, means for feeding a ribbon having composition ribs between said carriage and press in unison with advance movement of said carriage, means for reciprocating said press while said carriage is in motion; and means cooperating between said press and carriage for compressing the composition ribs.
- In testimony whereof, I have affixed my signature.
- GEORGE A. BUTTRESS.
